VIBRATION APPARATUS

Charles Leavell, Washington, D. C., and John A. Wheeler, Princeton, N. J., assignors to Mechanical Research Corporation, a corporation of Pennsylvania

Application September 2, 1941, Serial No. 409,306

9 Claims. (Cl. 121—36)

This invention relates to apparatus with which the varying reactive force of a vibratory body can be converted to a reactive force of substantially constant value.

Everyone familiar with drilling, demolition and riveting practice, is aware of the devastating effects of percussive tools upon their operators. In fact, many attempts have been made to absorb or eliminate the shock attending the use of such tools, as will be evidenced by the extent of the patented art. But apparently, until now, no satisfactory solution has been proposed.

Perhaps the most common mode of attacking the problem in connection with pneumatic or other percussive tools is through the interposition of shock absorbing springs at various points between the motors of such tools and their handles. Whereas some of the vibrational forces would be dissipated in this manner, the magnitude of the objectionable forces is still appreciable, and the physical and nervous reactions upon the operators still excessive.

Pneumatic cushioning has been tried also, as disclosed for example, in the patent to Noble, 2,061,806, dated November 24, 1936, wherein an air cushion of constant volume is employed. With such construction, a relatively large proportion of the vibrational forces is nevertheless transmitted to the operator. And in the disclosures of the patents to Simpson et al., 1,221,615, dated April 3, 1917, and Faudl, 1,924,234, dated August 29, 1933, cylinder and piston structures have been interposed between the motors and their supporting handles, with substantially equal fluid pressures applied to opposite ends of the pistons, whereby the operator is still subjected to a large measure of the shock produced.

Springs in combination with fluid pressure have been proposed as well, as described in the patent to Collins, 1,792,893, dated February 17, 1931, combining the advantages of these systems as well as their disadvantages. And another prior art structure seeking to achieve the desired result appears in the patent to Benedict, 1,792,888, dated February 17, 1931, wherein there is produced at certain times, equalization of the pressures on opposite ends of the piston defined by the housing of the tool motor; and in this construction there will likewise be marked variations in the pressure of the entrapped air which constitutes the cushion.

The research resulting in the present invention has led to a discovery which is as startling due to its simplicity as it is because of its practical importance. It has been found that if a vibrat-

ing body (exemplified by a pneumatic paving breaker) is constrained to "float" between unequal fluid pressures of substantially constant values, a constant force can be applied to a support (handle in the case of the paving breaker) for the body which will counteract the variable forces producing the vibration so that the vibratory body can be supported without vibratory forces reaching the support. Thus the device accomplishes the purpose of converting a vibratory recoil into a constant force.

The present invention comprises a vibratory body (such as a pneumatic tool) related to a support through relatively reciprocable elements provided with a suitable seal between them. In this manner, surfaces arranged on opposite sides of the seal may be exposed to the required unequal fluid pressures of substantially constant values. During normal operation of the apparatus, one of the elements assumes a position intermediate 10 the ends of its stroke as result of the application of a constant force supplementing the lower fluid pressure in opposition to the higher one.

One practical embodiment of the invention 15 contemplates that the reciprocable elements assume the form of a cylinder and piston system. Under these conditions, packing rings may constitute the seal and the opposed pressures will be applied to the ends of the piston. One end of the 20 piston may be exposed to atmospheric pressure under certain circumstances, while the other may be subjected to a subatmospheric pressure. Or, one end may be exposed to superatmospheric pressure while the other is presented to atmospheric pressure. Whatever the pressure sources 25 and values may be, they should be unequal and substantially constant. And it should be understood that the difference between these constant pressures may be changed in various ways to suit 30 conditions encountered in practice. In the case of a manually operated pneumatic tool, the difference in the opposed pressures should be of such value that an operator of average size and strength by supplementing the force of the lower 35 pressure, can overcome the larger one to produce such relative movement of the tool and handles as to bring the piston to a position intermediate 40 the ends of its stroke. In other applications, there will be an added force of some kind to accomplish a similar result.

In case a subatmospheric pressure applied to 45 the piston or equivalent element approaches the zero pressure of a vacuum, then the more nearly a perfect vacuum is maintained, the greater will 50 be the effect to eliminate the transmission of

vibration to the supporting structure. In such a case it is proposed to provide an outwardly opening check valve on the corresponding cylinder end for communication with atmosphere during relative movement in one direction to permit the escape of any entrapped air.

A pneumatic tool embodying this invention will preferably have such a piston-cylinder or other suitable connection between the body of the tool containing the usual mechanism and its support or housing carrying one or more actuating handles.

Typical applications of the invention will be understood more readily with reference to the attached drawings wherein:

Fig. 1 is an elevation, partially in section, illustrating one form of the invention;

Fig. 2 is a plan of the tool of Fig. 1;

Fig. 3 is a sectional elevation illustrating a modified form of the invention;

Fig. 4 is a section taken along line 4—4 of Fig. 3; and

Fig. 5 is a section taken along line 5—5 of Fig. 3.

As depicted in Figs. 1 and 2, a pneumatic tool 20 comprising the usual operating mechanism is supplied with compressed air through an inlet pipe 22 and is provided with a suitable exhaust port not shown. From the sides of the tool casing, two or more arms 24 project for a short distance, whereupon they are bent or otherwise provided with rods 26 extending longitudinally of the tool casing and carrying at their ends suitable packed pistons 28. These pistons are reciprocably received in closely fitting cylinders 30 carried by a supporting assembly comprising a shield 32 and handles 34. The pistons may be said to "float" in the cylinders since they are unrestricted except for the provision of stops to prevent separation of the elements. The pneumatic tool together with its pistons and rods is relatively movable with respect to the cylinder and shield assembly. At their upper ends, the cylinders are provided with resilient bumpers 36 which may be held in position by threaded spiders 38 which provide central bushings 39 for guiding the rods 26 and the lower ends of the cylinders are likewise provided with resilient bumpers 40 suitably held in position. As shown in Figs. 1 and 2 the upper ends of the cylinders are exposed to atmospheric pressure while the lower ends are provided with outwardly opening check valves 42 to permit the expulsion of any entrapped air when the pistons are pushed downwardly.

The admission of air from the supply pipe 22 is controlled by a valve 44 of the usual type, operated through a Bowden wire 46 by a lever 48 carried by one of the handles 34. By interconnecting the handle and the tool through such a flexible cable, there will be no interference with the relative movement of the parts.

In operation, still considering the form shown in Figs. 1 and 2, an operator will apply the tool to the work and bear down upon the handles 34 with sufficient force to move the pistons with respect to their cylinders to an intermediate position of their stroke, such as has been depicted in Fig. 1 of the drawings. Depression of the lever 48 will then admit air to the tool and its operation will begin. By moving the pistons to the positions shown, the zero pressure of a vacuum will be approached sufficiently to establish a substantially constant pressure in the chambers 50 defined between the lower ends of the pistons 28

and the closed ends of the cylinders, despite the volumetric variation of these chambers in operation. There will then be a constant subatmospheric pressure (the substantially constant pressure of the vacuum) in these chambers maintained against constant atmospheric pressure by a constant downward force applied to the handles by the operator. Should the operator reduce the force applied to the handles, the piston will move downward towards the lower end of the cylinder. Reversal of the downward force applied by the operator, as by lifting the tool by its handles, to move it to a new position will result in the piston moving to the extreme lower end of its stroke due to the weight of the tool, accompanied by opening of check valve 42 should an appreciable quantity of air be entrapped in the chamber 50. Thus, a new application of downward force to the handles will again establish the vacuum whenever desired or required.

The modification depicted in Figs. 3, 4 and 5 is based upon somewhat similar principles, but instead employs a superatmospheric pressure in opposition to the combination of atmospheric pressure and the force of the operator applied to the tool handles. In this case the tool 20 has been shown as having a packed upper end 52 and an enlarged lower end 54 received in a cylinder 56 whose lower end is open to atmosphere and whose reduced upper end is closed by a cap 58. The body 60 of the tool below the packed end is shown as provided with a pair of bearing elements 61 engaging the wall of the cylinder 56, with slots 62 between them for cooperation with threaded pins 64 which prevent relative rotation of the tool with respect to the cylinder and serve to impose desired limits upon the longitudinal movement of the tool within the cylinder. In some cases, the ends of the pins received in the slots may be provided with soft resilient rings 66, such as rubber, for the reduction of noise and shock. The entire casing or cylinder 56 below the piston 52 is maintained at atmospheric pressure by suitably venting it with slots 67 defined between webs 69.

The supply of air in this form of the invention is delivered from a relatively large tank 68 or other source of substantially constant pressure through a hose line 70 and a port 72 into the chamber 74 defined at the upper end of the cylinder between the cap 58 and piston 52. The diameters of the hose line and port are sufficiently large in relation to the diameter of said chamber so that despite movement of piston 52 in the chamber, the pressure therein will remain approximately equal to the pressure in the supply tank, and will therefore provide a substantially constant force to be overcome at the handles. A valve stem 76 projecting from the upper end of the tool is depressible by actuating the lever 48 mounted on one of the handles through a Bowden wire 46. The tank 68 is shown as receiving its supply of compressed air from a pump 78 which delivers through a pressure regulator 80. The regulator setting may be adjusted for various values to suit the tool, type of work and operator.

Since the lower end of the cylinder is open to atmosphere, it is required in this construction that the force applied to the handles by the operator, plus the force of atmosphere, overcome the force of the supplied air to move the piston structure to a point, intermediate its stroke such as has been depicted in Fig. 3 of the drawings.

By the expression "substantially constant" as applied to the forces and pressures set forth in

the present specification and claims, is intended such a degree of constancy as will sensibly reduce vibration in a particular system to which the invention is applied, in accordance with the same principles as apply to the complete elimination of vibration where absolutely constant values are obtainable. In those cases in which subatmospheric pressures are used, as a perfect vacuum is approached, small pressure differences will naturally represent large pressure ratios. In order to clarify the use of terms as much as possible, in the description and claims here involved, where substantially constant forces and pressures are alluded to, differences in such values, not ratios, are the criteria.

Whereas but two examples of the present invention have been illustrated and described, it will be evident that it is applicable to many uses not specifically mentioned and many forms of construction not depicted in the drawings. The real scope of the invention will be measured therefore by the following claims.

We claim:

1. In combination with a vibratory body and a support therefor, a vibration converter comprising piston and cylinder structure relating said body and support, means for imparting to said piston a position intermediate the ends of its stroke during normal operation of said body, means providing a seal for said piston with respect to said cylinder, and means maintaining the opposed ends of said piston at unequal fluid pressures of substantially constant values, one of said fluid pressures being atmospheric.

2. In combination with a vibratory body and a support therefor, a vibration converter comprising piston and cylinder structure relating said body and support, means for imparting to said piston a position intermediate the ends of its stroke during normal operation of said body, means providing a seal for said piston with respect to said cylinder, means for establishing fluid pressures at the ends of said cylinder, and said piston in said intermediate position having its opposed ends exposed to unequal fluid pressures of substantially constant values, one of said fluid pressures being subatmospheric.

3. In combination with a vibratory body and a support therefor, a vibration converter comprising piston and cylinder structure relating said body and support, means for imparting to said piston a position intermediate the ends of its stroke during normal operation of said body, means providing a seal for said piston with respect to said cylinder, means for establishing fluid pressures at the ends of said cylinder, and said piston in said intermediate position having its opposed ends exposed to unequal fluid pressures of substantially constant values, one of said fluid pressures being atmospheric and the other subatmospheric.

4. In combination with a pneumatic tool and a supporting casing therefor, a vibration converter comprising cylinder means provided by said casing receiving reciprocable piston means provided by said tool, handles carried by said casing for moving said casing and thereby imparting to said piston means a position intermediate the ends of its stroke for normal operation of said

tool, means providing a seal between said piston and cylinder means, and means maintaining the opposed ends of said piston means at unequal fluid pressures of substantially constant values, one of said pressures being atmospheric.

5. In combination with a vibratory body and a support therefor, a vibration converter comprising piston and cylinder structure relating said body and support, means providing a seal for said piston with respect to said cylinder, means maintaining the opposed ends of said piston at unequal fluid pressures of substantially constant values, and means for applying a force in opposition to the greater of said fluid pressures to move said cylinder and thereby to impart to said piston a position intermediate the ends of its stroke for normal operation of said body, one of said pressures being atmospheric.

6. In combination with a pneumatic tool and a supporting casing therefor, a vibration converter comprising a housing for said tool defining a piston and a cylinder defined by said casing for reciprocably receiving said piston, handles projecting from said casing for moving said casing and thereby imparting to said piston a position intermediate the ends of its stroke for normal operation of said tool, piston packing for maintaining a seal between the opposite ends of said piston, and means maintaining the opposed ends of said piston at unequal fluid pressures of substantially constant values, one of said pressures being atmospheric.

7. In combination with a vibratory implement and a support therefor, a device comprising a cylinder receiving a piston interconnecting said implement with its support, means for imparting to said piston a position intermediate the ends of said cylinder during operation of said implement, means for establishing fluid pressures at the ends of said cylinders, said piston having an end normally exposed to atmospheric pressure, and another end defining with said cylinder a chamber at subatmospheric pressure.

8. In combination with a vibratory implement and a support therefor, a vibration converter comprising piston and cylinder articulating means relating said implement and support, said cylinder having one end in constant communication with atmosphere and the other end provided with an outwardly opening check valve, whereby relative movement of said piston in one direction creates a vacuum in said other end of the cylinder, and means for applying a force to said combination for creation of said vacuum.

9. In combination with a vibratory body and a support therefor, a vibration converter comprising piston and cylinder structure relating said body and support, said piston being freely floating in said cylinder and assuming a position intermediate the ends of its stroke during normal operation of said body, means providing a seal for said piston with respect to said cylinder, and means maintaining the exposed ends of said piston at unequal fluid pressures of substantially constant values, one of said pressures being atmospheric.

CHARLES LEAVELL.
JOHN A. WHEELER.
